UNITED STATES PATENT OFFICE.

HOWARD DEAN STARR, OF LONG BEACH, CALIFORNIA.

MEANS FOR MAINTAINING A RESERVE SUPPLY OF FUEL IN FUEL TANKS.

Application filed March 25, 1925. Serial No. 18,146.

This invention relates to variable level outlets for fuel tanks, which may be manually adjusted to create or tap a reserve supply.

5 An object of my invention is to automatically insure a reserve supply of fuel at each filling of the tank.

Other objects are to provide a means of maintaining a reserve fuel supply, which is 10 simple in construction, inexpensive to manufacture and which may be readily installed in the tank.

Another object is to provide a yieldable means, manually controlled to vary the outlet from the tank.

15 A further object is to provide means controlled by the tank filler cap, to automatically insure a reserve supply of fuel.

A feature of my invention is the provision 20 of a connection between the filler cap and the reserve fuel supply means, whereby the removal of said filler cap from the tank will operate through the connection to insure a reserve fuel supply.

25 Other objects, advantages and features of invention may appear from the accompanying drawing, the subjoined detailed description and the appended claims.

The accompanying drawing illustrates 30 the invention.

Figure 1 is a plan view of my apparatus as applied to a tank, a portion of which is shown.

Fig. 2 is a longitudinal sectional view of 35 my apparatus, showing a reserve supply of fuel in the tank.

Fig. 3 is a fragmentary partly sectional view of a slightly modified form of apparatus for maintaining a fuel reserve.

40 Fig. 4 is a sectional view on line x^4 , Fig. 3.

This invention is particularly applicable to motor vehicle fuel tanks, but may also be applied to other tanks, if desired.

The tank 1 has a threaded inlet 2 into 45 which a suitable cap 3 fits. An outlet boss 4 is provided in the bottom of the tank 1, and is internally threaded to receive the externally threaded upper end 5 of a fitting 6.

The lower end 7 of the fitting is internally 50 threaded to receive a valve 8 from which valve the supply pipe 9 extends. A stand pipe 10 is fitted into the upper end of the fitting 6 and rises above the bottom of the tank 1, any desired distance. This pipe is 55 preferably sweated into a hole in the top of the fitting 6, although any other desirable

method of joining the pipe and fitting may be employed.

A hole or port 11 is provided in the top of the fitting 6, adjacent the pipe 10, and on 60 or about the level of the bottom of the tank.

A valve rod 12 is seated in the port 11, and extends upwardly through a hole 13 in the top of the tank 1, and projects a short 65 distance above the top of said tank.

A conical valve seat 14 is formed on the bottom of the rod 12, and a pin 15 depends from the rod, and extends through the port 11, which assures the proper return and seating of the seat 14.

The rod 12 is yieldably held on its seat in 70 the port 11 by a spring 16 surrounding said rod and bearing against a collar 17 on the rod and against the top of the tank. The collar may be a washer held in position by 75 a pin 18 extending through the rod or any other desirable means may be employed.

To seal the hole 13, a fibrous washer 19 surrounds the rod 12 within the tank and the spring 16 bears against it to hold it against 80 the tank about said hole.

Normally the rod 12 is seated in the port 11, permitting no fuel to pass through said port. When the fuel level is above the 85 pipe 10, it will flow through said pipe, fitting 6, valve 8 and pipe 9. The pipe opening being above the bottom of the tank; a reserve will remain which cannot be tapped through the pipe.

The rod 12 may now be raised to open the 90 port 11, thus permitting all of the fuel in the tank to be drained therefrom through the port 11. The rod is held in a raised position by a pin 20, extending through an elongated hole 21 in the rod, the pin resting 95 on the top of the tank 1.

The rod 12 is positioned to one side of the cap 3, and a flexible connection 22 such as a chain joins the pin and cap. A bolt 23 secures the chain to the cap. In assembling, with the cap 3 seated, a hole for the bolt 23 is drilled on the side nearest the rod 12, so that when the pin 20 is in said 100 rod the chain 22 will be taut.

Thus when the cap is rotated to remove 105 it and refill the tank, the chain 22 is automatically pulled by this motion and the pin 20 retracted, which permits the spring 16 to automatically force the rod 12 to a seat in the port 11, and thus insure a reserve 110 supply of fuel.

In practice, I have found it advisable to

tilt the pipe 10 at a slight outward angle so it will escape the rod 12 when threading the fitting 6 into the tank.

In the modified form of my invention shown in Figs. 3 and 4, the fitting 25 threaded into the bottom of the tank has a tubular extension 26 rising therefrom into the tank. A slot 27 is formed in extension 26 and extends the length thereof, and to the level of the bottom of the tank.

A rod 28 similar to rod 12 is mounted in and slidably fits the extension 26. This rod normally seats on a seat 29 in the fitting 25, and is provided with a duct 30 which extends from above the top of the extension 26, when the rod is seated, and communicates with the bore of the fitting 25.

The operation and position of the rod 28 is identical to that of the rod 12 already described.

When the rod is seated the fuel passes through the duct 30 leaving a reserve and when the rod is raised the fuel flows through the slot 27 into the fitting 25, and drains the tank.

In assembling my device, I first insert the rod 12 through the outlet boss 4, and then pass the upper end of said rod through the hole 13. I then insert pin 15 into the orifice 30 that forms the valve seat and screw the fitting 6 home, after which valve 8 and pipe 9 may be connected to the fitting to complete the assembly.

The assembly of the device shown in Fig. 3 will be apparent from the foregoing.

I claim:

1. In combination with a tank, a fitting mounted in said tank, said fitting having an opening above the bottom of said tank and a second opening at the bottom of the tank, a rod seated in said second opening

and extending through the top of the tank, resilient means normally holding said rod seated; a pin adapted to extend through said rod to hold it unseated; a filler cap, a flexible connection between said pin and said cap, said connection being adapted to retract said pin when the cap is being removed.

2. In combination with a tank, a fitting threaded into said tank, a tube rising from said fitting into the tank, said fitting having a port at the bottom level of said tank, a rod normally seated in said port and extending through the top of said tank, a spring surrounding said rod and urging it to its seat in the port; a pin adapted to engage said rod to hold it unseated, a filler cap, and a flexible connection between said cap and said pin, whereby said pin is retracted when the cap is being removed.

3. In combination with a tank having a filler cap, a fitting mounted in said tank, said fitting having an opening above the bottom of said tank and a second opening at the bottom of the tank, a rod seated in said second opening and extending through the top of the tank, resilient means normally holding said rod seated; said rod having a slot therein adjacent the top thereof, said slot being adapted to be raised above the top of the tank when the rod is unseated, a pin adapted to extend through said slot and rest on said tank to hold the rod unseated, and flexible means secured to said pin and cap, whereby said pin is retracted when the cap is rotated to remove the same from the tank.

In testimony whereof, I have hereunto set my hand at Los Angeles, California, this 5th day of March 1925.

HOWARD DEAN STARR.
